UNITED STATES PATENT OFFICE.

HENRY ROTHERMEL, OF MANSFIELD, OHIO.

SLATE-CLEANER AND ERASER.

SPECIFICATION forming part of Letters Patent No. 416,807, dated December 10, 1889.

Application filed September 7, 1889. Serial No. 323,305. (No model.)

To all whom it may concern:

Be it known that I, HENRY ROTHERMEL, a citizen of the United States, residing at Mansfield, in the county of Richland and State of Ohio, have invented certain new and useful Improvements in a Combined Slate-Cleaner and Pencil-Eraser; and I do declare the following to be a full, clear, and exact description of the invention, such as will enable others skilled in the art to which it appertains to make and use the same.

The invention relates to improvements in a slate-cleaner and pencil-eraser for school purposes, and its nature and distinctive characteristics are fully described hereinafter.

In the accompanying drawings I illustrate a slate-cleaner and pencil-eraser embodying the invention.

Figure 1 is a view of slate-cleaner and pencil-eraser. Fig. 2 is a central vertical longitudinal section of same, showing its general construction.

In the drawings, A indicates a soft-rubber case, which is half-spherical in form and constructed concave in the bottom, the case being formed hollow to form a chamber, said walls and bottom of case to be of a parallel thickness. A circular opening D is made through the case at the crown to connect with the chamber C. The chamber C is for the purpose of holding a sponge, which is placed in the chamber C through the opening D.

B is a rubber eraser, which is constructed conical in form. Said eraser is so constructed on its lower end to form a plug E large enough to impinge the inner walls of the opening D, the said plug being made smaller than the

base of the cone, forming a flange to prevent any leakage of the water from the sponge.

The operation of the device is as follows: 40 When it is only necessary to erase pencil-marks, the eraser B is left in its relative position; but should the operator wish to use the device to clean the slate the eraser B is removed. Then by a pressure upon the lower 45 portion of the half-sphere the concave bottom G will press the sponge upward, and a portion of same will protrude through the opening D a sufficient distance to allow the operator to clean the slate. Relax the pressure upon the case, and the sponge will return into the chamber.

The invention being so simple in construction, it is unnecessary to explain the same more fully.

Having thus described my invention, what I claim as new, and desire to secure by Letters Patent, is—

1. A combined pencil-eraser and slate-cleaner, consisting of a hollow case, an eraser 60 having its lower end fitting in said case and concaved to receive a sponge, and having its upper end tapering to form an eraser, substantially as shown.

2. The combination of the case A, pencil-eraser B, and sponge H, as described, and for the purpose specified.

In testimony whereof I affix my signature in the presence of two witnesses.

HENRY ROTHERMEL.
